PAPER BOX

Henry Hirsch, Jersey City, N. J.

Application April 6, 1938, Serial No. 200,519

2 Claims. (CL. 229—41)

This invention relates to boxes and the improvements are directed to a novel form of container adapted to receive wearing apparel, such as suits, dresses and laundered articles.

5 An important object of the invention resides in the provision of a box of the above-mentioned character that may be composed of light-weight material, such as paper, and which is susceptible of folding to a collapsed condition to facilitate storage and transportation of a large number within a small amount of space.

10 Another object is to provide means in the form of a filler, or the like, that normally abuts each corner of the box, and which is arranged in juxtaposition to the contiguous portions of the walls and ends at the corners of the box to reinforce and maintain the same in an erect position.

15 A still further object of the invention is to so arrange the respective fold lines between the box ends and sides, and the corner filler, so that a continuous surface, or non-foldable section is presented adjacent a fold line on said filler and the ends of the box.

20 In practical fields the details of construction may necessitate alterations, falling within the scope of what is claimed.

25 The invention comprises further features and combination of parts, as hereinafter set forth, shown in the drawings and claimed.

30 In said drawings:

Figure 1 is a perspective view of the box with the sides and ends in an erect position.

Fig. 2 is a perspective view showing the box folded and collapsed.

35 Fig. 3 is a fragmental perspective of a corner of the box showing the end and side walls, and the filler, in a partially collapsed condition.

Fig. 4 is a perspective view of a filler.

40 Fig. 5 is a fragmental perspective view of a corner of the box with the filler removed.

Fig. 6 is a plan view of the blanks from which the box and fillers are formed.

45 Referring now more in detail to the accompanying drawings wherein like characters of reference denote similar parts throughout the several views, 5 indicates the bottom of the box and 6 and 7 oppositely disposed ends and oppositely disposed sides, respectively. As shown in Fig. 6 the blank is creased along the lines 8 and 9 and also along lines 10 and 11 whereby said ends and sides may be folded to an erect position with the tabs 12, coextensive with sides 7, suitably affixed to the adjacent ends, as shown in Fig. 5. It will also be observed that each of said sides 7 is provided with 55 a fold line 13 which extends in each instance from

the corners of the bottom of the box at an acute angle to the jointure between the ends and sides. In view of this arrangement the ends and sides may be folded onto the bottom of the box, the sides 7 being further foldable on lines 13 to permit 5 complete collapsing to a substantially flat condition. While this arrangement permits the stacking of the boxes within a small amount of space, it is obvious that means must be provided to reinforce the corners of the box in order to maintain 10 the sides and ends in an erect position. To this end I have provided filler elements which are formed from cardboard, or the like, to form blanks 14, (see Fig. 6), the same being creased on line 15 to form sections 16 and 17, whilst sections 16 15 are creased at 18, said crease or fold line extending from the lower portion of said crease line 15 and at an acute angle therewith, as viewed in Fig. 4. With the box and its ends and sides assembled, as pointed out hereinbefore, the fillers 14 are applied inside the corners of the said box by suitably affixing the ends of sections 16 and 17 to ends 6 and sides 7, (see Fig. 1), the two 20 fold lines abutting at the corners as shown, and it will be observed the fold line 13 of the sides 7 abuts the unfolded section 16 whilst the fold line 18, of section 17, abuts the unfolded portion of the ends 6. Thus the weakness of a fold line is compensated by an area devoid of a crease or fold line. 25 This is a feature of some importance. The 30 method of collapsing the corners of the box is illustrated in Fig. 3 wherein it will be observed the filler at each corner is depressed inwardly on the line 15, the section 17 folding on line 18, whilst the sides 7 fold inwardly on crease line 13, said 35 sides 7 and ends 6 now collapsing onto the bottom of the box as shown in Fig. 2. When erecting the sides and ends of the box the filler at each corner folds on lines 15 and 18 and as the sections 16 and 17 contact the adjacent portions of the sides 40 and ends of the box the conditions shown in Fig. 1 are obtained. This arrangement admirably reinforces the corners of the box and assures that the ends and sides shall remain in an erect position until the fillers are collapsed. 45

While the foregoing description is directed in detail to the box proper it will be understood that the cover portion will preferably be formed in the same fashion with slightly enlarged dimensions to fit over said box.

50 I claim:

1. A box comprising oppositely disposed walls and oppositely disposed ends foldably connected to said walls, each of the walls having a fold line extending at an acute angle from each corner of 55

- the box, a bottom connecting said walls and ends, and a filler attached to said walls and ends adjacent each corner, the section of the filler attached to said ends also having a fold line extending at an acute angle from each corner of the box, the arrangement being such that the walls and ends may be folded upon the bottom or maintained in an erect position without folding said ends.
- 10 2. A box comprising a bottom and oppositely disposed walls and ends having corner crease lines, each of the walls having a fold line extending angularly from each corner crease line to permit folding of the walls and ends onto the

bottom, and a filler attached to said walls and ends, said filler having a crease line abutting said corner crease line when the walls and ends are erect, the section of the filler attached to an end of the box having a fold line extending angularly from the corner of the box to permit folding of the filler in conjunction with the folding of said walls and ends, the arrangement being such that the fold lines of the walls and filler, respectively, are re-inforced by a continuous or non-foldable section of the walls and filler, respectively, thus compensating for the weakness of a fold line.

5 10 HENRY HIRSCH.
